UNITED STATES PATENT OFFICE.

JOHN W. KENYON, OF MANCHESTER, ENGLAND.

STEAM-ENGINE RECORDER.

SPECIFICATION forming part of Letters Patent No. 232,978, dated October 5, 1880.

Application filed April 30, 1880. (No model.) Patented in England April 1, 1878.

To all whom it may concern:

Be it known that I, JOHN WILLIAM KENYON, a subject of the Queen of Great Britain and Ireland, and residing at Manchester, 5 county of Lancaster, England, have invented certain Improvements in Steam-Engine Indicators, (for which I have obtained a patent in Great Britain, No. 1,278, April 1, 1878,) of which the following is a specification.

10 The object of my invention is to so construct a steam-engine indicator that its indicating power can be readily changed, and means may be provided for disconnecting the paper-cylinder from the actuating-cord. I 15 employ a curved tube formed on the "Bourdon" principle, instead of a piston, and to disconnect the paper-cylinder I raise it out of gear with a separate wheel upon which the cord acts.

20 In the accompanying drawings, Figure 1 is a view, partly in section, of a complete indicator. Fig. 2 represents the lower part of the paper-cylinder and the cord-wheel and lifting attachment drawn to a larger scale. Fig. 4 is 25 a plan of the same parts. Fig. 3 is a view of the lifting attachment. Fig. 5 shows the manner in which the paper-cylinder and cord-wheel engage together.

In Fig. 1, *a* is the curved tube. *b* is the paper-cylinder. *c* is the cord-wheel, and *d* is the lifting attachment. The part *a* is formed of hollow hard brass or metal tube of an oval form in cross-section, as in the case of the ordinary "Bourdon" tube, or it may be of any 35 suitable sectional form. One end of this tube is brazed, soldered, or attached to the male part of a conical coupling, *e*. The two parts of the coupling are forced together by means of a nut, *f*, so as to firmly secure the tube to 40 the body-casting of the indicator, and at the same time to make a steam-tight joint. When the indicator is coupled up to the steam-cylinder in the ordinary manner, the steam pressure or vacuum has access through a passage, 45 *g*, to the interior of the tube, and causes the free end *h* to move up and down or to and fro in proportion to the extent of such pressure or vacuum. This free end is connected in any suitable manner with the multiplying-levers *i* 50 of the ordinary Richards pencil-motion, or with an arrangement of levers substituted therefor.

In the example the end *h* terminates in a pin, upon which is mounted a short tube, to which is jointed one end of a rod, *j*. The other end of this rod is screwed into a ball which is 55 socketed between the two levers *i*, so as to form a ball-and-socket joint. The short tube at *h* is retained by a removable button. To exchange the curved tube *a* for a stronger or weaker tube, as may be required, the button 60 is removed and the short tube slipped off the pin at *h*. The tube *a* is now uncoupled at *e*, and the fresh tube is coupled up, and the attachment at *h* is slipped on the end of the pin and secured with the button. The body-casting 65 is formed with a turned pillar, *k*, upon which the arm-piece *l* swivels, in the same manner as the corresponding piece swivels upon the cylinder in the ordinary Richards indicator.

70 The paper-cylinder *b* is mounted upon an inner cylinder, *m*, which is formed with a tubular boss bored to slide upon the ordinary fixed stud *n*. A spiral spring, *t*, tends to force the cylinder *m* toward the cord-wheel *c*. The 75 cord-wheel is formed with a box, *o*, in which is the ordinary volute spring, and is mounted to rotate upon the stud *n*, being rotated in the one direction by the pull of the cord, and in the other direction by the action of the volute 80 spring. A notch is formed in the lower edge of the cylinder *m*, and the cord-wheel is provided with a tooth, as indicated by Fig. 5; or the disposition of the parts may be reversed. When the tooth and notch engage, the paper- 85 cylinder and the cord-wheel rotate together, as if they were attached, as is the case in the ordinary indicator. When the cylinder *m* is raised so that the tooth clears the notch, the cord-wheel may still revolve, but the paper- 90 cylinder will remain at rest.

A forked lever, *p*, is hinged at *r* to a pillar. The two rounded ends of the fork pass below the flange on the lower end of the cylinder *m*. A trigger, *s*, is employed to act upon this lever. When this trigger is moved into the position indicated by the dotted lines in Fig. 3, the forked end of the lever *p* is raised, and, acting on the flange on the cylinder *m*, raises the paper-cylinder and disengages it from the 100 cord-wheel. When the preparations for taking a diagram are completed, a touch of the

finger upon the trigger releases the lever *p* and the paper-barrel is pressed into gear by the spiral spring. The trigger-piece is stepped, so as to lower the paper-cylinder by two stages.

5 The intention is, that the first step shall lower the cylinder until the flange lightly presses upon the tooth, so that, as it were, the tooth may feel for the notch without turning the paper-cylinder. This lifting attachment may 10 be varied.

I claim as my invention—

1. The combination of the curved tube connected to the pencil-motion of a steam-engine indicator with the body-casting, adapted to be 15 coupled to the steam-cylinder, and having a conduit, *g*, and a detachable coupling connecting said conduit to the curved tube, substantially as described.

2. The combination of the cord-wheel and

paper-cylinder *b*, adapted to slide toward and 20 from such wheel, with devices, substantially as described, for connecting and disconnecting the two.

3. The combination of the spring *t* with the paper-cylinder and cord-wheel, the two being 25 provided with corresponding teeth and notch, as and for the purpose specified.

4. The combination of the cord-wheel and cylinder with lever *p* and trigger *s*, substantially as set forth.

In testimony whereof I have signed my name to this specification in the presence of 30 two subscribing witnesses.

J. W. KENYON.
